ABSTRACT OF THE DISCLOSURE

Disclosed is a high gain wide bandwidth cascaded multi-stage transistor video amplifier, each stage of which has substantially the same gain and substantially the same bandwidth. The output of each stage is coupled to the input of the next subsequent stage by an emitter follower which has its input coupled directly to the output of the preceding stage. In addition an emitter follower couples the output of the last stage to the output of the amplifier. Each stage is provided with both adjustable high frequency current peaking negative current feedback and mid-frequency flattening negative voltage feedback to thereby provide a wide bandwidth with a sharp high frequency roll-off. The disclosed transistor video amplifier is unusual in that its overall bandwidth is substantially the same as the bandwidth of a single stage thereof, although the total gain of the amplifier is substantially equal to the product of the gains of the cascaded stages.

This invention relates to transistor amplifiers and, more particularly, to an improved broad-band, high-gain transistor amplifier.

One approach now employed to achieve a high gain, broad bandwidth transistor amplifier is the use of cascaded frequency compensated transistor amplifier stages. It is known that such cascaded amplifiers have a total risetime which is equivalent to the square root of the sum of the squares of the risetime of an individual stage of the amplifier. The risetime is inversely proportional to the bandwidth. Hence, each stage of a normally cascaded amplifier has a higher frequency response than the resultant composite. This approach thus results in the loss of bandwidth for the increased gain obtained.

In a second approach, a distributed amplifier using delay line techniques has been employed to afford a large bandwidth. However, the total voltage gain obtained by this approach is equal to the sum of the voltage gains of the individual stages instead of their product as is the case with the cascaded amplifier approach first mentioned above. Thus, in the second approach, gain is, in effect, traded off for the bandwidth obtained.

In addition to the disadvantages mentioned above, amplifiers of the type described have proven difficult to design, as individual tuning and adjustment for the stages therein are required; transistors have to be selected and often times, to achieve proper biasing and temperature stability, two power supplies are required.

It is therefore an object of the present invention to provide an improved broadband, high gain transistor amplifier.

Another object is to provide an improved broadband, multi-stage transistor amplifier whose gain is the product of the individual stages.

Another object is to provide an improved broadband, multi-stage, high-gain transistor amplifier whose bandwidth is approximately that of the individual stages.

Another object is to provide an improved broadband, high-gain, transistor amplifier operating from one power supply.

These and other objects are achieved according to one

2

embodiment of the invention by employing a transistor amplifier stage including a common emitter transistor amplifier circuit configuration with collector-to-base feed back and emitter peaking for frequency compensation. The stage further includes an output emitter follower transistor circuit configuration through which the transistor amplifier stage can be coupled to a succeeding similar stage. A high-gain, large bandwidth amplifier is obtained by series-connecting a proper number of the amplifier stages, the resulting composite amplifier operating without the disadvantages and limitations as to gain or bandwidth encountered in the use of previously proven amplifier.

In order that the invention may be more clearly understood, reference is now made to the following description in connection with the accompanying drawing in which

FIG. 1 shows a transistor amplifier stage constructed according to one embodiment of the invention, and

FIG. 2 shows a broadband high-gain transistor amplifier using five stages as shown in FIG. 1.

Referring to FIGURE 1, a transistor 9 has a base electrode 18, a collector electrode 17 and an emitter electrode 19. The emitter 19 is connected to a point of reference potential such as ground through series resistor 7, 8. A variable capacitor 13 is also connected between the emitter 19 and ground. The series combination of resistors 7 and 8 provide the necessary bias voltage at the emitter 19 to operate the transistor 9 in Class A mode. Resistor 8 is by-passed to ground by a capacitor 14 to prevent this resistor 8 from introducing degeneration. The capacitor 13 is used as an emitter peaking capacitor which operates to provide high frequency compensation in conjunction with the resistor 7. The collector 17 of transistor 9 is connected to one end of a load resistor 16. The other end of the load resistor 16 is connected to a common bus. The bus provides a connection via a resistor 15 to the positive terminal of a source of unidirectional potential 23. Also connected to this bus is a resistor 2 which in conjunction with a resistor 3 forms a biasing network for the base 18 of the transistor 9. The junction of resistors 2 and 3 is connected to the base, 18, the other end of the resistor 3 being connected to ground.

A series network consisting of a resistor 6, an inductor 5, and a capacitor 4 is connected between the collector 17 and the base 18 of the transistor 9. This network provides base-to-base collector feedback and is effective at the low frequency end of the amplifier stage's frequency response to provide gain stabilization. As the frequency of input signal energy applied to the base 18 of transistor 9 via a coupling capacitor 1 is increased, the network consisting of resistor 6, inductor 5 and capacitor 4 has less effect on the gain.

The collector 17 of transistor 9 is directly connected to the base 21 of a second transistor 10. Transistor 10 is employed in an emitter follower configuration. The emitter 22 of transistor 10 is connected to ground through a resistor 12. The collector 20 of transistor 10 is connected directly to the common bus. A capacitor 11 is connected between ground and the junction of the collector 20 and the resistor 15. The combination of the resistor 15 and capacitor 11 serves as a filtering network to eliminate any power supply ripple that may be present from the power source 23. The filter comprising capacitor 11 and resistor 15 also serves to isolate the common bus of a succeeding stage as shown in FIG. 1 from the common bus of a succeeding stage connected in the manner shown in FIG. 2.

Briefly, the above transistor amplifier stage consists of a high gain Class A amplifier consisting of transistor and associated circuitry, using both emitter peaking and collector-to-base feedback frequency compensation. The output from the collector of transistor 9 is fed directly

onto the base of an emitter follower comprising transistor **10** and associated circuitry which serves to isolate the Class A amplifier from a succeeding stage.

FIGURE 2 shows five stages as shown in FIG. 1 connected together to form a broadband, high gain amplifier. Identical components are given the same reference numerals and the third stage is bracketed for clearer representation. The numerals assigned in FIG. 1 to the base, collector and emitter electrodes of the transistors **9** and **10** have been eliminated in FIG. 2 for simplicity. Each of the stages has a specified gain in decibels. The gain is a function of the transistors **9** and **10** and the collector load **16** of the transistor **9**, the compensating network consisting of resistor **6**, inductor **5** and capacitor **4**, and the combination of the resistor **7** and the peaking capacitor **13**. The gain of the composite amplifier shown in FIGURE 2 is the sum of the decibel gain of each stage, where decibel gain is defined as twenty times the log-to-the-base-ten of the voltage gain. In the case shown the total gain of the amplifier would be five times the gain in decibels of each stage. In addition to the high gain, the bandwidth of the composite broadband amplifier is approximately equal to the bandwidth of the individual stage so that bandwidth is not traded off for the gain. The components value from stage-to-stage can be identical, except for the setting of the variable capacitor **13** which may differ for each stage. As each stage is isolated from the succeeding stage by an emitter follower, capacitor **13** in each stage can be set without the need for further adjustment to provide maximum bandwidth of that stage. One thereby achieves maximum bandwidth for the composite amplifier.

In operation an input signal is applied through a resistor **25** to the base of the transistor **9** in the first stage from a source **24** which could be an oscillator, pulse generator, or any other suitable signal source. The resistor **25** is made approximately equal to the output impedance of the emitter follower stage.

A typical example of component values employed in a broadband amplifier constructed in the manner of that shown in FIGURE 2 are given below in Table 1.

TABLE 1

Capacitor 1	—	μfd	3,000
Resistor 2	—	ohms	18,000
Resistor 3	—	do	2,700
Capacitor 4	—	μf	1,000
Inductor 5	—	henries	.07
Resistor 6	—	ohms	620
Resistor 7	—	do	100
Resistor 8	—	do	270
Transistor 9	—	2N918	
Transistor 10	—	2N918	
Capacitor 11	—	mfd	.1
Resistor 12	—	ohms	2,000
Capacitor 13	—	μfd	4-45
Capacitor 14	—	mfd	.02
Resistor 15	—	ohms	22
Resistor 16	—	do	2,000
Battery 23	—	volts	+24
Resistor 25	—	ohms	50

The amplifier shown in FIGURE 2 and built with the component values indicated in Table 1 has a frequency response in excess of 300 megacycles and a gain in excess of 50 decibels; provided proper high frequency construction techniques are utilized. An amplifier is provided which exhibits both high gain and broad bandwidth, there being no significant trade-off in its operation as between gain and bandwidth.

The addition of more stages than the number shown in FIGURE 2 will increase the gain of the amplifier by a factor of approximately 10 decibels per stage, while maintaining approximately the same bandwidth.

While N-P-N transistors are shown, P-N-P transistors can be used by reversing the power supply polarity

in a manner understood in the art. The component values indicated in the example given are only typical of one embodiment and can be altered to fit the requirements of a particular application.

What is claimed is:

1. A cascaded video amplifier comprising a plurality of stages each of which has substantially the same first given gain, first given bandwidth, first given input impedance and first given output admittance; and a like plurality of coupling means each of which except one couples the output of a preceding one of said plurality of stages to the input of the next subsequent one of said plurality of stages of said amplifier and said one coupling means couples the output of the last of said plurality of stages to the output of said amplifier, each of said coupling means having substantially the same second given gain, second given bandwidth, second given input admittance and second given output impedance; wherein said first given gain is large relative to unity and said second given gain is substantially unity, said first given bandwidth is significantly smaller than said second given bandwidth, said second given input admittance is insignificant with respect to said first given output admittance over the entire first given bandwidth, and said second given output impedance is insignificant with respect to said first given input impedance over the entire first given bandwidth, whereby said amplifier provides a total gain for an input signal applied to the input of the first stage thereof substantially equal to the product of said first gains of all said plurality of stages and has an overall bandwidth substantially equal to said first given bandwidth.

2. The amplifier defined in claim 1, wherein each of said stages is a transistor stage and wherein each of said coupling means is an emitter follower.

3. The amplifier defined in claim 2, wherein the input of each emitter follower is directly connected to the output of the preceding transistor stage.

4. The amplifier defined in claim 1, wherein said first given bandwidth is wide and has a sharp high frequency roll-off.

5. The amplifier defined in claim 4, wherein each of said stages includes frequency-responsive negative feedback means for widening said first given bandwidth and providing said sharp high-frequency roll-off.

6. The amplifier defined in claim 5, wherein said frequency-responsive negative feedback means includes both a high-frequency current peaking negative current feedback means and a mid-frequency flattening negative voltage feedback means.

7. The amplifier defined in claim 6, wherein said negative current feedback means is adjustable.

8. The amplifier defined in claim 1, wherein said plurality is at least equal to three.
